UNITED STATES PATENT OFFICE

90,872

DESIGN FOR AN ADVERTISING NOVELTY

Edward C. H. Denton, Newton Center, and Albert H. Clime, Brookline, Mass.

Application August 12, 1933. Serial No. 49,012

Term of patent 3½ years

To all whom it may concern:

Be it known that we, EDWARD C. H. DENTON, and ALBERT H. CLIME, citizens of the United States of America, residing at Newton Center and Brookline, respectively in the counties of Middlesex and Norfolk, respectively and State of Massachusetts, have invented a certain new, original, and ornamental Design for an Advertising Novelty, of which the following is a specification, reference being had to the accompanying drawing, forming part thereof.

In the drawing,

Fig. 1 is a front view of an advertising novelty showing our new design; and

Fig. 2 is a rear perspective thereof showing rotatable spools which are adapted to hold and operate a strip of paper or film displaying successive or continuous pictures movable across the back of the stage.

We claim:

The ornamental design for an advertising novelty, as shown and described.

In testimony whereof we affix our signatures.

EDWARD C. H. DENTON.

ALBERT H. CLIME.
